UNITED STATES PATENT OFFICE

2,661,521

YARN STRETCHING DEVICE

Elliot Stone, Edward James Sparke, and Joseph Patrick Muldowney, London, England, assignors to British Enka Limited, London, England, a British company

Application July 7, 1952, Serial No. 297,466

Claims priority, application Great Britain July 28, 1951

7 Claims. (Cl. 28—71.3)

1

The present invention relates to stretching devices for textile yarn and is especially, although not exclusively, applicable to the stretching or so-called pre-stretching of rayon.

The conventional yarn stretching machines usually apply a constant extension or a constant tension to a yarn. Thus in those cases where the yarn initially is itself of varying extensibility, as in the case of pot spun rayon where the extensibility of the yarn increases from the outer part of the cake inwardly, this variation still persists after stretching.

One feature of the present invention consists in passing the yarn through a given path from which it is withdrawn at a speed related to but higher than that at which the yarn is fed into said path whereby to stretch the yarn.

In most applications of the invention it will be necessary to treat the yarn whilst passing through said given path so as temporarily to alter the physical character of the yarn by swelling to increase its stretchability whereby to enable the yarn to be permanently or substantially permanently stretched. This treatment may consist of a steaming treatment or a moistening treatment or treatment by moisture and heat whereby to reduce the swelling of the yarn.

A further feature of the invention consists in gradually varying the degree of stretch by gradually varying the relationship between the speed of the yarn on entering and leaving said path.

A still further feature of the invention consists in gradually varying the degree of stretch as referred to above in dependence upon the increasing size of a package of yarn wound from said path or upon the diminishing size of a package or cake of yarn from which yarn is drawn into said path.

A device according to the present invention for applying stretch to textile yarn embodies a yarn feeding and withdrawing means and spaced guide means such as pulley wheels which in conjunction with said yarn feeding and withdrawing means define a given path through which the yarn can be passed in a bight, said feeding and withdrawing means consisting of two freely rotatable stepped godets or rollers arranged side by side so that on entering said given path the yarn can be passed in loops around the godet steps of smaller diameter and on leaving said path it can be passed in loops around the godet steps of larger diameter to cause the yarn to be fed into said path at a speed lower than that at which it is withdrawn and thus to be stretched.

As a rule it will be advisable to include in the 55 ing yarn package which may be formed on the

2

said given path means such as a steaming device or a moistening device or a moistening and heating device for temporarily altering the physical character of the yarn as referred to above.

5 The godets are preferably of the same diameter i. e. their larger steps are of the same diameter and their smaller steps are of the same diameter, and the axes of the godets whilst lying in a common plane are preferably arranged at a small angle to one another to ensure automatic spacing of the loops of yarn passing therearound. If desired the relative angularity of the godet axes may be adjustable to enable the spacing of the yarn loops on the godets to be adjusted.

10 15 It will be appreciated that by means of the present invention the degree of extension applied to the yarn can be accurately controlled and will depend upon the difference in diameter between the large and small steps of the godets.

20 The degree of extension applied to the yarn may be varied in a gradual and controlled manner by employing godets of which the smaller steps are tapered in the same axial direction and by providing means for adjusting, in the axial

25 direction of the godets, the position at which the yarn is fed onto the smaller steps of the godets. In this way the rate of feed of the yarn into the said path can be varied whilst maintaining a constant speed of withdrawal of the yarn so that the degree of extension of the yarn is thereby varied.

30 35 A still further feature of the invention consists in progressively varying the degree of extension applied to the yarn substantially in dependence upon the varying extensibility of the yarn itself.

Thus in the treatment of pot spun rayon the present invention enables the degree of extension applied to the yarn to be progressively increased as the yarn is drawn from a cake from the outside thereof. This is achieved according to the present invention by causing a guide for leading the yarn onto the tapered steps of godets to be progressively moved axially of the tapered steps towards the narrower end thereof in dependence upon the increasing diameter of a rotating package which draws the yarn from the godet steps of larger diameter. For this purpose the yarn guide may be loaded for movement in one direction as by means of a spring or weight or both and may be restrained from movement in that direction by means of a wedge element movable under the control of a feeler such as a button guide engaging the surface of the rotating

cheese former of an ordinary coning or winding machine such for example as a Hobourn coning machine made in Great Britain or a coning machine made in U. S. A. by the Universal Winding Machine Company.

The invention includes combing or winding machines which include a device for applying stretch to the yarn as herein described.

The invention is further described with reference to the accompanying drawings in which:

Fig. 1 is a side elevation of a coning or winding machine with the invention applied thereto.

Fig. 2 is a somewhat diagrammatic perspective view of the device of the present invention.

Fig. 3 is a side view of the godets to a larger scale, and

Fig. 4 illustrates a detail.

The drawings illustrate an arrangement suitable for applying a gradually increasing degree of extension to the yarn of a cake of pot-spun rayon.

In Fig. 1, a coning or winding machine 1 as made by the Universal Winding Machine Company in U. S. A. is shown in outline in relatively light lines. The cheese former 2, traverse head 3 and traverse frame 4, pivoted at 5, are part of the standard machine, the function of the traverse head 3 being to feed the yarn back and forth along the cheese former 2 as the cheese former rotates. The device of the present invention is applied to the coning machine 1 and embodies stepped godets 6, 7 and fixed guide pulleys 8, 9 around which the yarn is passed through a substantially inextensible path which includes a steaming tube 10 to which steam is fed by a steam connection 11 to escape at the ends of the tube.

Pot-spun rayon yarn 12 is drawn from a cake 13 and passes through a tension gate 14 (shown diagrammatically in Fig. 2) to the tapered smaller steps 15, 16 of the godets 6, 7. The yarn is guided onto the steps 15, 16 by a yarn guide 17 in the form of an eye at the upper end of the tension gate 14. The axial position of the yarn guide 17 in relation to the godets is adjustable as will be hereinafter described.

After passing in loops several times around the steps 15, 16 the yarn leaves the steps 15, 16 as indicated at 18 (Fig. 2) and passes over fixed guide pulley 9, upward through steaming tube 10, over fixed guide pulley 8, and from thence passes to the larger steps 20, 21 of the godets 6, 7. After passing several times around the larger steps 20, 21 the yarn passes as at 22 to the cheese former 2 on which it is wound into a cheese, being guided back and forth along the former 2 by button guide 23 which rests against the yarn on the cheese former 2 and reciprocates back and forth in known manner along the traverse head 3.

As shown in Fig. 3 the spindles 24, 25 of the godets 6, 7 are arranged at a slight angle to one another. This is to ensure that the loops of yarn passing around the godets will automatically space themselves from one another. The angularity of the spindle 25 relatively to the spindle 24 can be adjusted by raising or lowering the right hand end of spindle 25. In this way the spacing of the yarn loops on the godets can be adjusted.

The tension gate 14 is pivoted at 27 (Fig. 2) and is loaded by means of a weight 28 and a spring 29 for clockwise movement about its pivotal axis 27. Such clockwise movement is

controlled by means of a wedge 30 which lies between the lower part of the tension gate 14 and a fixed post 31. The wedge 30 is guided in a groove 32 formed in the lower part of the fixed post 31. The wedge is pivoted at 33 to balance weight 34 of the traverse frame 4. The angularity of the traverse frame 4 is governed by the button guide 23 which engages the yarn wound on the cheese former 2 so that as more and more yarn is wound on the cheese former 2 the button guide 23 is gradually displaced by the increasing bulk of yarn on the cheese former to cause angular displacement of the traverse frame 4 in a clockwise direction whereby gradually to withdraw the wedge 30 to the left as viewed in Fig. 2 thereby allowing the tension gate 14 and the yarn guide 17 to be gradually angularly displaced in a clockwise direction so as to move the yarn guide 17 axially of the godets towards the narrower end of the tapered steps 15, 16. Thus as the yarn is progressively withdrawn from the cake 13 and wound on the cheese former 2, the rate of feed of the yarn into the yarn path or circuit defined by the pulleys 8, 9 will be gradually reduced whilst the rate of withdrawal of the yarn therefrom will remain constant. Thus the degree of extension of the yarn will be gradually increased as more and more yarn of increasing extensibility is withdrawn from the cake 13.

We claim:

1. A device for applying stretch to a textile yarn embodying means for winding the yarn onto a former, spool or the like, a feeler adapted to engage the yarn on the former and to be displaced as the diameter of the yarn on the former increases, a feeding and withdrawing means and spaced guide means such as pulley wheels which in conjunction with said guide means define a given path through which the yarn can be passed in a bight, said feeding and withdrawing means consisting of two freely rotatable stepped godets or rollers arranged side by side of which the smaller godet steps are tapered in the same axial direction, and a guide for leading yarn onto the tapered godet steps which guide is adjustable in the axial direction of said godets under the control of said feeler so that on entering said given path the yarn can be fed into said given path by the tapered godet steps at a speed which is an adjustable fraction of the speed at which it is withdrawn by the larger godet steps whereby to be stretched to a variable extent in dependence upon the displacement of said feeler.

2. A device according to claim 1 embodying means arranged in said given path for temporarily altering the physical character of said yarn to enable the yarn to be substantially permanently stretched.

3. A device for applying stretch to a textile yarn embodying means for winding the yarn onto a former, spool or the like, a feeler adapted to engage the yarn on the former and to be displaced as the diameter of the yarn on the former increases, a feeding and withdrawing means and spaced guide means such as pulley wheels which in conjunction with said guide means define a given path through which the yarn can be passed in a bight, said feeding and withdrawing means consisting of two freely rotatable stepped godets or rollers arranged side by side of which the smaller godet steps are tapered in the same axial direction, and a guide for leading yarn onto the tapered godet steps which guide is adjustable in the axial direction of said godets under the con-

trol of said feeler so that on entering said given path the yarn can be fed into said given path by the tapered godet steps at a speed which is an adjustable fraction of the speed at which it is withdrawn by the larger godet steps whereby to be stretched to a variable extent in dependence upon the displacement of said feeler, and an open-ended tube enclosing a limited portion of the path of travel of the yarn and duct means leading to the tube near its lower end to enable a fluid such as steam to be fed to the tube for the purpose of temporarily changing the character of the yarn whereby to enable the yarn to be substantially permanently stretched.

4. In a machine for winding yarn including a rotatable receiver upon which the yarn is wound and a feeler which is displaceably mounted and biased for engagement with the yarn being wound on the receiver and to be displaced as the diameter of the yarn on the receiver is increased during a winding operation, the combination of a feeding and withdrawing means and spaced guide means such as pulley wheels which in conjunction with said guide means define a given path through which the yarn can be passed in a bight, said feeding and withdrawing means consisting of two freely rotatable stepped godets or rollers arranged side by side, the smaller steps of which godets are tapered in the same direction, and a yarn guide for leading the yarn onto the godet steps of smaller diameter, said guide being adjustable in the axial direction of said godets under the control of said feeler.

5. In a winding machine according to claim 4 an open-ended tube enclosing a limited portion of the path of travel of the yarn and duct means leading to the tube near its lower end to enable a fluid such as steam to be fed to the tube for the purpose of temporarily changing the charac-

ter of the yarn whereby to enable the yarn to be substantially permanently stretched.

6. In a winding machine according to claim 4 a pivoted lever supporting said feeler, said lever being biased in a direction tending to keep the feeler in contact with the yarn on the receiver, a fixed abutment, a supporting means for said yarn guide pivotally mounted near to the fixed abutment, bias means tending to displace the supporting means towards said fixed abutment, and a tapered member disposed between the fixed abutment and the supporting means for controlling the position of the yarn guide said tapered member being connected to said pivoted lever supporting said feeler whereby to enable the feeler to control the position of the yarn guide in relation to the tapered godet steps.

7. A winding machine according to claim 6 in which the supporting means for the yarn guide embodies a tension gate on which the yarn guide is mounted.
